UNITED STATES PATENT OFFICE.

ARCHIBALD MACKINNON, OF TUCKAHOE, NEW YORK.

WINDOW CONSTRUCTION.

1,269,475.

Specification of Letters Patent. Patented June 11, 1918.

Application filed October 4, 1916. Serial No. 123,672.

To all whom it may concern:

Be it known that I, ARCHIBALD MACKINNON, a subject of the King of Great Britain, and a resident of Tuckahoe, in the county 5 of Westchester and State of New York, have invented a new and Improved Window Construction, of which the following is a full, clear, and exact description.

This invention relates to window constructions and deals particularly with the novel combination of window frame, revolving sashes and screens.

The general objects of the invention are to improve and simplify the construction 15 and operation of structures of this character so as to be reliable and efficient in use, of durable and substantial form, and so designed as to insure rain-, wind- and dust-proofness.

20 A more specific object of the invention is to provide a novel construction of window frame and novel means for suspending the sashes so that the sashes can be revolvably suspended directly on the counterbalance 25 weight chains, the sashes revolving on horizontal axes when the sashes are in lowered position.

Another specific object of the invention is the provision of a simple, novel and effective 30 screen which embodies a frame slidably mounted in the window frame and lying between the window sashes so as to take the place of the usual parting strip, the screen being composed of a holding frame which 35 can remain in the window frame, and the screen proper can be detached therefrom.

With such objects in view, and others which 40 will appear as the description proceeds, the invention comprises various novel features of construction and arrangement of parts which will be set forth with particularity in the following description and claims appended hereto.

In the accompanying drawing which illustrates 45 one embodiment of the invention and wherein similar characters of reference indicate corresponding parts in all the views,

Figure 1 is a front view of the window with portions of the frame broken away to 50 illustrate the details of construction, the lower sash being partly raised and the screen down;

Fig. 2 is a vertical section on the line 2—2, Fig. 1.

Fig. 3 is a horizontal section on the line 55 3—3, Fig. 1;

Fig. 4 is a vertical section taken parallel with the window sashes, and the section being in the plane of the screen;

Fig. 5 is a detail section of the lower part 60 of the window frame with the screen partly raised;

Fig. 6 is a detail sectional view on the line 6—6, Fig. 2;

Fig. 7 is a fragmentary perspective view 65 of the window screen; and

Fig. 8 is a detail sectional view on the line 8—8, Fig. 2.

Referring to the drawings, A designates the window frame, B and C the lower and 70 upper sashes, and D the window screen. The window frame includes the sill 1, which is of usual construction except that a stop 2 may be employed for engagement by the bottom of the lower sash to prevent the latter from moving outwardly. The sides 3 of the window frame are each formed with a groove 4 extending the full height of the frame to form guides for the side edges of the screen D, and parallel with the groove 80 3 are additional grooves 5 and 6 for receiving the suspension chains for the lower and upper sashes. These grooves extend downwardly from the flush pulleys 7 to a point considerably short of the window sill. The 85 lintel 8 of the window frame is of usual construction except that it has the deep recess 9 to allow the top portion of the lower sash to rise to a considerable height for providing clearance when the lower sash is 90 lowered and rotated.

As shown in Fig. 6, the upper portion of the screen groove 4 in the left hand side of the window frame is somewhat deeper than the lower portion so as to provide for lateral movement of the 95 screen to disengage it from the window frame, there being in this deepened portion 4^a of the groove 4, leaf springs 10 which normally retain the right edge of the screen engaged in the groove 4 in the right side of 100 the window frame.

The upper and lower sashes B and C are of usual construction, except that the upper cross bar 11 of the lower sash and the bottom cross bar 12 of the upper sash are not 105 beveled and do not overhang to meet, as is usual in sashes. As shown in Fig. 2, the bars 11 and 12 have flat opposed faces and

are spaced apart so as to accommodate between the sashes the screen D. The sashes B and C are suspended respectively by chains 13 and 14 which pass over the pulleys 5 7, and the ends of these chains disposed in the weight boxes 15 of the window frame are provided with counterbalancing weights 16. The chains are disposed in the grooves 5 and 6 and their ends are provided with 10 hooks or equivalent devices 17 for engaging with pivot pins 18 in the stiles 19 of the sashes. These pins 18 are disposed midway the ends of the stiles 19, so that the sashes can swing on horizontal axes in balanced 15 condition. In this construction it will be noted that the sashes are directly pivoted on the suspension chains, and as the chains are disposed in the grooves in the window frame the edges of the sash stiles can lie close to 20 the inner surfaces of the sides of the window frame. The lower sash must be in lowered position in order to revolve on its pivots 18, and to permit this the inner beads or 25 stops 20 have lower sections *a* mounted on the window frame by hinges 21, so that they can be swung from the full to the dotted line position, Fig. 3. The lower sash can then be turned almost half way around to the dotted-line position, Fig. 2, so that the 30 outer surface of the pane can be readily cleaned. It is to be understood that the screen D must be in fully raised position before either sash can be turned.

The upper sash must be also lowered before it can be revolved, and to permit it to be revolved the outer beads or stops 22 on the sides of the window frame extend only about half way down the latter from the top, as shown in Fig. 2, and in line with 35 these beads and considerably below the same are depressible stops 23 set in the sides of the window frame so as to prevent the lower sash from outward displacement when it is in lowered position. When the sash is lowered it can be turned by throwing the lower portion outwardly and the upper portion inwardly, but in order to do this the resistance of the yielding stops 23 must be overcome. This is also true when the lower 40 sash is turned. To hold the upper sash from moving inwardly when the screen is lowered, as shown in Fig. 2, thin side strips 24 are set into the upper portions of the grooves 4 to engage the stiles of the sash 45 C, and a stop strip 25 fastened to the lintel engages the top bar of the window sash C. These strips 24 and 25 may be pieces of sheet metal angles secured in place by suitable fasteners. These strips contribute in 50 producing extremely tight joints between the upper sash and the window frame.

The screen D comprises a rectangular frame 26 slightly wider than the sashes, since the side edges thereof engage in the 55 grooves 4, and is about the same height as

the lower sash. Within this frame 26 is the screen body section 27, which is removably set in the frame 26 and held in any suitable manner, as, for instance, by upwardly extending pins 28 on the top of the 70 body section 27, which pins engage in sockets 29 in the top bar 30 of the holding frame 26. The bottom of the body section 27 is held in place by a button 31 on such body section, which engages behind a catch or stop 32 on 75 the bottom bar of the frame 26. This catch or keeper 32 may take the form of a grip or finger-hold, whereby the screen may be engaged for raising and lowering the same. While the screen as a whole can be removed, 80 it is preferable to leave the frame 26 in place and remove only the body section 27 of the screen during the season of the year when screens are not required. As shown in Figs. 85 5 and 7, the vertical bars of the frame 26 have tongue portions 26^a tapering in two planes, and the lower ends of the grooves 4 are so shaped that an extremely tight fit is obtained between the screen and the window frame when the screen is down. By 90 reason of this the screen frame 26 cooperates with the lower sash to insure tight joints in order to keep out wind, dust and rain.

The parting means between the upper and lower sashes is formed by the metal strips 95 24 and by the frame 26 of the screen. These two parts of the parting means are located in the grooves in the window frame and when the part 26 of the parting means is in raised position alongside of the stationary 100 part 24 of the parting means, either sash can be turned while in the lower part of the window frame, as explained.

A structure designed as illustrated and described is comparatively simple and inexpensive, enables sashes to be readily turned for cleaning the panes or for any other purpose, and rattling noises are eliminated and proofness against the entrance of rain, wind and air insured. 110

From the foregoing description taken in connection with the accompanying drawings, the advantages of the construction and method of operation will be readily understood by those skilled in the art to which the 115 invention appertains, and while I have described the principle of operation, together with the device which I now consider to be the best embodiment thereof, I desire to have it understood that the device shown is 120 merely illustrative and that such changes may be made when desired as fall within the scope of the appended claims.

Having thus described my invention, I claim as new and desire to secure by Letters 125 Patent:

1. The combination of a window frame having a groove extending from the top to the bottom of each side, upper and lower sashes each capable of turning on a hori- 130

zontal axis, and parting means between the sashes, said parting means comprising thin strips fastened in the upper portions of the grooves to engage with the upper sash when in normal position, and a frame sliding in the grooves and engageable with the lower sash, when in normal position, said frame being slidable upwardly in the window frame to lie alongside of the said strips for 10 permitting either sash to be turned.

2. The combination of a window frame having on the inner face of each side a longitudinal groove, upper and lower window sashes slidably mounted in the frame 15 and disposed at opposite sides of the grooves, means for supporting the window sashes and for permitting each to turn on a horizontal axis, and parting means located within each groove, each parting 25 means comprising a fixed strip lying along the upper sash and terminating short of the lower sash, and a slidible element in the groove adapted to occupy a position in the bottom of the frame to hold the lower sash

in place and adapted to move into the upper 25 part of the frame for permitting either sash when in lowered position to turn.

3. The combination of a window frame having on the inner face of each side a longitudinal groove, upper and lower window 30 sashes slidably mounted in the frame and disposed at opposite sides of the grooves, means for supporting the window sashes and for permitting each to turn on a horizontal axis, and parting means located with- 35 in each groove, each parting means comprising a fixed strip lying along the upper sash and terminating short of the lower sash, and a slidible element in the groove adapted to occupy a position in the bottom of the frame 40 to hold the lower sash in place and adapted to move into the upper part of the frame for permitting either sash when in lowered position to turn, said element being in the form of a frame extending from one side of the 45 window frame to the other and having means for removably holding a screen.

ARCHIBALD MacKINNON.
